CLAIM

The ornamental design for a flexible, multiple compartment medical container, as shown and described.

DESCRIPTION

FIG. 1 is a perspective view of an embodiment of a flexible multiple compartment medical container, showing our new design;

FIG. 2 is a front elevational view thereof;

FIG. 3 is a side elevational view of the right side thereof;

FIG. 4 is a back elevational view thereof;

FIG. 5 is a side elevational view of the left side thereof;

FIG. 6 is a top plan view of the container oriented as in FIG. 4; and,

FIG. 7 is a bottom plan view of the container oriented as in FIG. 4.
